UNITED STATES PATENT OFFICE.

WALTER C. SHOUP AND WALTER E. OLIVER, OF HOBOKEN, NEW JERSEY.

MANIFOLDING DEVICE FOR TYPEWRITING-MACHINES.

1,383,846.

Specification of Letters Patent. Patented July 5, 1921.

Application filed April 11, 1918. Serial No. 227,908.

To all whom it may concern:

Be it known that we, WALTER C. SHOUP and WALTER E. OLIVER, citizens of the United States, and residents of the city of Hoboken, 5 in the county of Hudson and State of New Jersey, have invented certain new and useful Improvements in Manifolding Devices for Typewriting-Machines, of which the following is a specification.

This invention relates, in general, to that class of manifolding devices in which a plurality of strips of fabric are arranged in superposition over a substantially flat writing bed or platen, with manifolding material 15 interposed between each two adjacent strips, so that matter inscribed upon the uppermost strip will be reproduced autographically upon the other strips. The present invention, however, has more specific reference to 20 a manifolding device in connection with which a typewriter machine of the sort commonly known as a "book typewriter" is employed for the writing operation.

In a co-pending application, filed October 25 19, 1916, Serial No. 126,622, we have referred at length to the commercial requirements of devices of the said general class, and to the various objections to those in use prior to the development of the invention upon which our 30 said application was based, laying especial stress upon the fact that, since it is customary to use with manifolding devices strips of paper or other fabric having forms initially inscribed thereupon, and since it is 35 necessary or desirable that matter written at certain points upon the uppermost of a plurality of superposed forms shall be reproduced at corresponding points upon the forms underneath, it is of the utmost importance that the means employed for advancing the strips over the writing bed shall be 40 adapted to insure substantially exact registration of the superposed forms at a predetermined point in their advancement. Our 45 said co-pending application discloses means by which the said requirements have been successfully and satisfactorily met, and said objections overcome, and similar means are employed in the manifolding device referred 50 to herein.

In the use of a typewriter for performing

the writing operation, however, other difficulties have been encountered, perhaps the most serious of which results from the fact that the manifolding devices with which 55 typewriters are used are generally employed for filling in relatively large forms, and for turning out a considerable number of autographic copies, as, for example, six or eight or even more. Since it has been the practice 60 heretofore, and has been necessary, to have the writing bed at least as long and as wide as the largest forms to be used therewith, the area of contact between said bed and the lowermost of the paper strips is so great, and the 65 frictional engagement between these two so pronounced, as to make it difficult to advance the strips, thereby necessitating the application of excessive force thereto; furthermore, the large area of contact between adjacent 70 strips, or between the strips and the manifolding material, does not, as might be supposed, appreciably decrease the likelihood of disarranging the superposed form, so as to 75 get them out of register, when advancing them. Then, too, the formation of what may be termed air pockets between the superposed strips, due almost entirely to the manner in which they have been supported by the writing bed heretofore, tends to cause disarrangement of the strips, and interferes seriously 80 with the production of clear manifold copies.

The principal object of the present invention is to provide means for surmounting the 85 said difficulties and overcoming the said objections by arranging for the use of a writing bed which may be much smaller, in at least one dimension, than the forms to be employed therewith. Other objects are to combine said means with the means disclosed in 90 our co-pending application aforesaid for insuring uniform advancement of the superposed paper strips, and with means for mechanically advancing the manifolding strips; also to accomplish the foregoing objects by 95 the use of mechanism that requires a minimum of manual attendance, is simple, dependable and unlikely to get out of order, has few wearing parts, is comparatively inexpensive, and is so designed and constructed 100 that all portions thereof are readily accessible for repairs and replacements.

The foregoing and other desirable features of our invention are fully set forth in the following description of the accompanying drawings, which form part of this specification, and in which—

5 Figure 1 is a sectional side elevation of our improved manifolding device;

Fig. 2 is a perspective view of the same, with the typewriter omitted;

10 Figs. 3 and 4 are enlarged detail views in sectional side elevation, showing two different positions of our improved writing bed;

Fig. 5 is an enlarged top-plan detail view 15 of the mechanism for advancing the paper strips and the manifolding strips;

Fig. 6 is an enlarged isometric detail view of the paper-strip-advancing mechanism;

20 Fig. 7 is an enlarged detail view, in sectional side elevation, showing the devices by means of which advancement of the paper strips is caused to be resumed after having been stopped automatically;

25 Fig. 8 is a detail view, in end elevation, of the mechanism for advancing the strips of manifolding material;

Fig. 9 is a sectional detail view taken substantially on line 9—9 of Fig. 5.

30 Referring now to the drawing in detail, the frame of our improved device is constructed of four similar uprights or legs, 5, 6, 7 and 8, preferably of metal tubing, secured together by means of tubing members 9, 10, 11, 12, 13 and 14. Mounted upon members 10 and 12 are the supports 15 and 16 for the typewriter 17, which is adapted to travel backward and forward on cogged rails 18 and 19 carried by said supports.

40 Six rolls of paper are shown, although it is manifest that a greater or less number may be employed if desired, said rolls being numbered, respectively, 20, 21, 22, 23, 24 and 25, and being rotatably mounted between 45 the horizontal members 26 and 27 connected with members 15 and 16 by members 28, 29, 30 and 31. As is the case in our copending application aforesaid, each of the strips of paper has holes initially punched or 50 otherwise formed therein at predetermined points, as indicated at 22^a, 24^a and 25^a. The five rolls of carbon paper, 32, 33, 34, 35 and 36, are rotatably mounted between members 37 and 38 at the left-hand side of the 55 frame (Fig. 2). The strips from the six paper rolls are led over suitable guide rollers located near the front of the frame, and thence rearwardly over the writing bed or platen 39, and the strips from the five rolls 60 of manifolding material are led over similar guide rollers, at right angles to the paper strips, each carbon-paper strip being interposed between its respective pair of paper strips, and the free ends of all five 65 of said manifolding strips are introduced

between two grip rollers, 40 and 41, which are of the same diameter, and are geared together so that when one of them is caused to revolve the others revolves at the same rate of speed, said grip rollers being thus adapted to advance the set of manifolding strips with substantial uniformity.

After passing over platen 39, the six paper strips are interposed between a roller 42 and a shaft 43, on the latter of which are 75 secured two similar annular disks, 44 and 45, of the same diameter as roller 42, shaft 43 being located vertically underneath roller 42 in position for said disks to coöperate with said roller in advancing said strips.

Said roller and said shaft are geared together so as to revolve at the same speed, and one end of shaft 43 is extended at 46 through and beyond typewriter support 16,

80 a bevel gear 47 being secured at the end of said shaft extension. A shaft 48 is rotatably mounted between two members 49 and 50 extending outward from typewriter support 16 at right angles thereto, a hand crank 51 being secured at one end of said shaft while 90

at its other end is secured a bevel gear 52 in mesh with bevel gear 47. Upon shaft 48, 95

between members 49 and 50, is loosely mounted a sleeve 53, and upon said sleeve

is secured an arm 54 having a pin-and-slot 100 connection with an arm 55 loosely mounted upon a reduced extension 56 of roller 40,

said arm 55 carrying a pawl 55^a adapted to engage a ratchet 57 secured upon said extension 56.

A finger 58 is secured to sleeve 105 53, so that by means of said finger said sleeve may be turned through a partial revolution, thereby turning roller 40, and thus also roller 41, through the medium of arms 54 and 55, pawl 55^a and ratchet 57, to advance the five strips of carbon paper.

A shaft 59, having a milled or knurled 110 knob 59^a at one end thereof, is located vertically below shaft 43, and one side of shaft 59 is cut away near each of its ends to form

a plane surface at the points where said shaft is embraced by slots 60^a in the brackets 60 in which roller 42 is journaled. Thus, when 115

said plane surfaces are uppermost, said roller is held yieldingly in its lowermost position by springs 61 secured near the lower ends of brackets 60, while, upon turning

shaft 59 through a partial revolution, roller 42 is moved upward away from shaft 43 120

against the action of springs 61. A shaft 125 62 is located below shaft 59, and nearer the front of the frame than the latter, and is held yieldingly against revolution in one direction by a spring 63. Upon shaft 62 is

loosely mounted a pawl 64, the hole therein 130 which embraces said shaft being of some-what greater diameter than the shaft, and

the free end of said pawl being adapted to contact with a cylindrical sleeve 65 loosely

135 mounted upon shaft 43 midway between:

disks 44 and 45, and to engage grooves 65^a two of which are formed diametrically opposite each other in the periphery of sleeve 65. An arm 66 is secured upon shaft 62 adjacent pawl 64, and to the free end of said arm is loosely secured a vertically-disposed plate 67 having two similar fingers 68 projecting from its upper edge in line with disks 44 and 45. Plate 67 is held in place 10 partly by arm 66, partly by a projection 69 on pawl 64, and partly by contact of fingers 68 with a horizontal plate 70 extending over pawl 64 and arm 66. Between sleeve 65 and disk 44 is interposed a loose spacing 15 collar 71, and between said sleeve and disk 45 is a loosely-mounted spring 72 the tendency of which is to cause sleeve 65 to revolve with shaft 43. A spring 73 tends to hold pawl 64 in its most advanced position toward 20 shaft 43, and arm 66 is provided with a lug 74 extending toward pawl 64, normally above and free from said pawl but in position to engage it upon downward movement of the free end of said arm.

25 As fully described in our co-pending application aforesaid, revolution of roller 42 and shaft 43 with its disks 44 and 45 will cause the superposed paper strips to be advanced until the holes therein are engaged 30 by said disks, whereupon advancement of said strips will cease, and their sidewise positions will be regulated by engagement of fingers 68 with said holes. Upon depressing fingers 68, and at the same time disengaging 35 pawl 64 from groove 65^a, in the manner described hereinafter, sleeve 65 is free to turn with shaft 43 sufficiently to advance the paper strips until the holes therein are no longer engaged by disks 44 and 45, where- 40 upon the groove in sleeve 65 which was last uppermost will be engaged by pawl 64, thus terminating revolution of said sleeve, and disks 44 and 45 will again be adapted to co- 45 operate with roller 42 in advancing the strips; meanwhile, the tendency of sleeve 65 to be revolved with shaft 43 will move pawl 64 to its farthest position away from said shaft, against the action of spring 73. A plate 75 located adjacent roller 42 serves 50 as a tearing blade by means of which the advanced portions of the paper strips may be detached manually.

Near the end of sleeve 53 which is adjacent bevel gear 52, is secured an arm 77 55 which is pivotally connected with an arm 77 secured to extension 62 of shaft 62, so that, upon turning sleeve 53 manually by means of finger 58, shaft 62 is turned against the action of spring 63, thereby depressing plate 67, and hence fingers 68, through the medium 60 of arm 66 secured upon shaft 62, while at the same time lug 74 on arm 66 moves pawl 64 downward and disengages the free end thereof from groove 65^a of sleeve 65, said 65 pawl being then moved forward by spring

73 to a position such that it will not again engage the same groove and upward movement of its free end will be limited due to its engagement with the circular periphery of sleeve 65. So long as the free end of pawl 74 75 is thus held in its depressed position, arms 54 and 55, and arms 76 and 77, will remain in the positions shown in dotted lines in Figs. 8 and 9, but, upon turning shaft 43 in advance, sleeve 65 will turn therewith until pawl 64 engages that one of the grooves 65^a which was last uppermost, whereupon shaft 62 will be turned by action of spring 63, and arms 54, 55, 76 and 77 will be returned to the positions shown in full lines in 80 Figs. 8 and 9. At the same time fingers 68 will be moved upward into yielding engagement with the lowermost of the paper strips, in position to engage the succeeding holes in the strips when they have been advanced 85 sufficiently.

Roller 41, which co-operates with roller 40 to advance the carbon-paper strips, is mounted in brackets 78, provided with springs 79 and movable by means of a shaft 80 having a milled or knurled knob 81 thereon, the functions and operation of said brackets, springs and shaft being similar to those of brackets 60, springs 61 and shaft 59.

The gear wheels 82 upon which typewriter 17 is mounted are adapted to travel upon the cogged rails 18 and 19, the teeth of said wheels being in mesh with those of said rails. Since the details of construction of the typewriter and the manner in which 95 it is caused to move backward and forward on its supporting rails form no part of the present invention and are old and well known, it is not thought necessary to describe them herein.

100 Platen 39 is rigidly supported between two vertical members 83, which are connected by two horizontal members 84 with two vertical members 85, which in turn are connected with two horizontal members 86 110 having grooves 87 therein, said grooves engaging lugs or other projections (not shown) on the typewriter 17. The frame which comprises members 83, 84, 85 and 86 is mounted upon wheels 88 adapted to travel 115 upon tracks 89, the latter being substantially horizontal throughout, except that they curve downward near their forward ends on account of the fact that the guide rollers over which the paper strips are led are below the plane of platen 39 and it is desirable that when said platen is in close proximity to said rollers it shall be at or near their level.

120 Disregarding movement of the typewriter transversely of the paper strips, which has no bearing upon the present invention, the operation of our improved manifolding device may be described as follows:—The writing operation is started with platen 39 125

in approximately the position indicated at 90 in Fig. 3, the length of members 86 of the frame which supports said platen and the location of grooves 87 therein being such that at all times the type, when the typewriter is operated, strike above said platen. As line after line is written, the typewriter is moved forward in the usual manner, and carries platen 39 therewith, until at the completion of the writing to be done on the set of forms then in use said platen arrives at approximately the position indicated at 91 in Fig. 4. The used set of forms are now advanced by turning hand crank 51, after having depressed finger 58 to release fingers 68 from the holes in said forms and disengage pawl 64 from groove 65^a, until advancement of the paper strips ceases upon engagement of disks 44 and 45 with the holes in the succeeding set of forms, whereupon the positions of said strips are regulated transversely by engagement of fingers 68 with said holes. Although depression of finger 58 for the purpose just referred to automatically causes advancement of the five carbon-paper strips, it is manifest that said strips may be advanced a greater distance or at any time by depressing said finger the necessary number of times, and that said strips will remain stationary if roller 41 be moved away from roller 40 by turning shaft 80.

It will be noted that, while the length of platen 39 is practically the same as, or slightly greater than, the width of the paper strips, the width of said platen is decidedly less than the length of any of the forms such as are used with manifolding devices—in fact, we have found in practice that the width of the platen need be very little greater than the height of the largest type employed on the typewriter. Manifestly, since the only obstruction between the guide rollers over which the paper strips are led and the advancing means (roller 42 and disks 44 and 45) is the extremely narrow platen 39, there is very little opposition to advancement of said strips, which is quite different from the condition that exists when the area of the platen is at least as great as that of the largest form to be used. Similarly, advancement of the strips of manifolding material is rendered far easier for the same reason and by the same means, and regulation of the sidewise positions of the paper strips by fingers 68 is facilitated. It will also be noted that, on account of the fact that the paper-contact surface of platen 39 is above the level of the uppermost points of both the guide rollers and disks 44 and 45, the paper strips are held upon the platen in the desired flat position without the necessity for extreme tautness of said strips, thereby still further affecting the ease with which said strips may be advanced, and the

likelihood that air pockets or cushions will be formed between the superposed strips is greatly lessened.

Various modifications of minor details of our improved manifolding device will doubtless readily suggest themselves to those skilled in this art, and we therefore do not desire to limit our invention to the exact construction shown and described.

We claim as new, and seek to protect by Letters Patent:—

1. The combination, with a typewriter, of a platen therefor located outside the frame thereof but movable therewith relative to the work sheet for line-space movement. 80

2. The combination, with a typewriter, of a platen therefor located outside the frame of said typewriter but movable therewith relative to the work sheet for line-space movement, and means connecting said typewriter and said platen, whereby movement of said platen is caused by movement of said typewriter. 85

3. The combination, with a typewriter and a support upon which said typewriter is movable, of a platen for said typewriter carried separately by said support but movable with the frame of said typewriter relative to the work sheet for line-space movement.

4. The combination, with a typewriter 95 having a definite total effective line-space movement relative to the work sheet, of a platen therefor movable relative to the work sheet for line space movement and located outside the frame of said typewriter, the 100 dimension of the writing surface of said platen in the direction of said line-space movement being less than that of said total line-space movement of the typewriter.

5. The combination, with a typewriter 105 having a definite total effective line-space movement relative to the work sheet, and a definite total effective movement transversely of said sheet, of a platen therefor and movable with the typewriter for line-space movement the area of the writing surface of said platen being less than the area covered by said line-space movement and transverse movement of said typewriter. 110

6. The combination, with a typewriter, of 115 a platen for said typewriter, and tracks independent of said typewriter upon which said platen is movable by line-space movement of said typewriter.

7. The combination, with a typewriter, of 120 a substantially plane-faced platen for said typewriter, and tracks independent of said typewriter upon which said platen is movable both by line-space movement of said typewriter and by return movement thereof 125 to initial position.

8. The combination in a manifolding device, of a plurality of superimposed sheets of paper each having a series of spaced holes arranged longitudinally thereof; a type- 130

- writing machine; a platen therefor located outside the frame of the typewriting machine and beneath the sheets, and said platen being movable with the typewriter relative 5 to the said strips of paper for line-space movement; and means for advancing said sheets of paper, from one of said holes to the next adjacent hole whereupon said sheet advancement will cease.
10. 9. The combination in a manifolding device, of a plurality of superimposed sheets of paper each having a series of spaced holes arranged longitudinally thereof; a manifolding sheet between each pair of said superimposed sheets of paper; a typewriting machine; a platen therefor located beneath the sheets of paper, and movable with the typewriter for line space movement; and means for advancing said sheets of paper 15 from one of said holes to the next adjacent hole whereupon said sheet advancement will cease.
10. The combination in a manifolding device, of a plurality of superimposed sheets 20 of paper each having a series of spaced holes arranged longitudinally thereof; a manifolding sheet between each pair of said superimposed sheets of paper; a typewriting machine; a platen therefor located beneath the sheets of paper and movable with the typewriter for line space movement; means 25 for advancing said sheets of paper from one of said holes to the next adjacent hole whereupon said sheet advancement will cease; and manually operated means for moving said manifolding sheets independently of the 30 said superimposed sheets of paper.
11. The combination in a manifolding device, of a plurality of superimposed sheets 35 of paper each having a series of spaced holes arranged longitudinally thereof; a typewriting machine; a platen therefor located beneath the said sheets and movable with the typewriter for line-space movement; means 40 for advancing said sheets of paper from one longitudinal opening to the next whereupon advancement of said sheets ceases; and manually operated means for again causing said advancing means to become effective.
12. The combination in a manifolding de- 45 vice, of a plurality of superimposed sheets of paper each having a series of spaced holes arranged longitudinally thereof; a type- writing machine; a platen located beneath the said sheets and movable with the type- 50 writer for line-space movement; means for advancing said sheets of paper from one longitudinal opening to the next whereupon advancement of said sheets ceases; and means for entering the hole in each sheet just be- 55 fore it reaches the advancing means whereby in case of unregistry of the sheets, they 60 will be brought into registry.
13. The combination in a manifolding de- 65 vice, of a plurality of superimposed sheets of paper each having a series of spaced holes arranged longitudinally thereof; a typewriting machine; a platen located beneath the said sheets and movable with the typewriter for line-space movement; means 70 for advancing said sheets of paper from one longitudinal opening to the next whereupon advancement of said sheets ceases; means for entering the hole in each sheet just before it reaches the advancing means whereby in 75 case of unregistry of the sheets, they will be brought into registry; and manually operated means for again causing said advancing means to become effective.
- In testimony of the foregoing, we have 80 hereunto set our hands in the presence of the subscribing witnesses.
